MAKING TURNOCKS

Joseph C. Fuller, Newton, Mass.

Application January 3, 1941, Serial No. 373,011

6 Claims. (Cl. 29—157.1)

This invention relates to the manufacture of valves of the rotary type for liquids or gases, which valves embody a casing or body in which there is a rotary member, the turning of which controls the passage of fluid through the valve. The object is to provide a procedure whereby such valves may be very simply and cheaply made, yet the fit of the rotary member and the alignment of the water-ways will nevertheless be exceedingly accurate. This I accomplish by molding the casing directly about the rotary member of the valve and thereafter forming water-ways through the so assembled casing and member.

My invention will be well understood by reference to the following description taken in connection with the accompanying drawing, wherein:

Fig. 1 is a central vertical section through a cock constructed in a manner exemplifying my invention;

Figs. 2 and 3 are central vertical sections illustrating various stages in the manufacture of the cock shown in Fig. 1;

Fig. 4 is a view similar to Fig. 3 showing another type of valve;

Fig. 5 is an elevation of a plug of somewhat different construction; and

Fig. 6 is a view similar to Fig. 3 showing a partially completed valve or cock embodying the plug shown in Fig. 5.

In Fig. 1 I have shown a valve embodying a casing or body 8, here shown as connected by a union 10 with a pipe 12 and having a fluid passage or water-way 14 therethrough which is intersected by the rotary plug 16 having an opening 18 which in one position of rotation aligns with the passage 14 to permit the flow of fluid. The valve may be of any suitable exterior formation and may be completed by additional parts, if desired, but in the drawing it has been shown as a generally straight member having a simple straight passageway therethrough.

Figs. 2 and 3 show steps in the manufacture of the valve shown in Fig. 1. Referring to Fig. 2, I form a blank plug 16, conveniently of metal, by any suitable operation or series of operations producing a body which generally, except for such portions as, for instance, the handle 20, which will be exterior to the body in the completed valve, is in the form of a solid of revolution. Thus in the example shown the main body is frusto-conical with a cylindrical extension 22 from the smaller base and a cylindrical stem 24 to which the lever handle 20 is connected. The

parts 22 and 24 serve somewhat in the manner of trunnions in the completed valve, as is clear from Fig. 1. In the particular modification illustrated, annular grooves 26 are provided near the bases of the frusto-conical body with which may be assembled gaskets 28 of any suitable material, such, for example, as the well known asbestos and graphite compositions or a composition of asbestos fibers and synthetic resin. I have referred to the plug as shown in Fig. 2 as a "blank" because it has no water-way or opening 18 therethrough, but at this stage has an unbroken wall in the form of a surface of revolution. In Fig. 2 the plug is illustrated in a mold 30 having a cavity therein corresponding to the casing for the plug in the valve to be formed and in the example illustrated it is positioned within the core space in the mold by means of the extension 22 and the stem 24. In the figure I have also shown the mold as provided with cores 32 corresponding in position to the water-way 14 in the completed valve but not, however, extending to the plug.

The body of the valve is molded directly about the plug and when removed from the mold 30 has the form shown in Fig. 3 with the body 8 provided with an imperforate wall exactly conforming to and fitting the blank plug 16. It will be understood that the plug is suitably treated, as will be understood in the art, to prevent adherence of the molded body thereto and to leave the same free for rotation within the integrally formed body which encloses the same as the result of the molding operation.

I use the word "mold" herein to include both the significance sometimes also expressed by the word "founding," that is, the casting of molten metal, for instance, by the process of die-casting, and also other operations usually or properly called molding, such as shaping from plastic material thereafter subjected to some treatment such as vulcanizing to set the same; the sintering together of powders under pressure and heat as in "powder metallurgy"; or the coalescence of suitable material under heat, as in the case of phenol formaldehyde condensation products or other "artificial resins."

In Fig. 3 I have partly illustrated a drill 36 graphically to indicate the next step of piercing as by drilling a water-way through the body 8 of the valve and the plug 16 across the opposing blank walls which are present at the stage illustrated in Fig. 3. Where the cores 32 are used, openings 34 will be formed in the body and the drilled hole will connect these openings which

will merge into the water-way 14 shown in Fig. 1 and the drilled hole will also form the passage 18 in the plug in exact alignment with the passage 14. In the example shown the gaskets 28 are molded within the integral body and form packings above and below the position of the water-way. By proper manipulation these may be loose or may turn with the plug or may be held gripped in the molded body.

The method of manufacture will be seen to be very simple, yet a perfect fit is obtained without the necessity of accurate fitting or of grinding together of the parts and the necessary passages in the body and valve are formed by a single piercing operation in accurate alignment.

In Fig. 4 I have shown a modified form of valve with a plug 16a formed with a stem 24a and handle 20a but with no extension from the lower end of the plug and having a casing 8a molded thereabout. The water-way may be formed in the valve shown to define an angle, the vertex of which is in the plug. A passage 38 may be pierced through the casing and into the plug axially of the latter, as indicated by dotted lines, and may meet an opening 14a, herein shown as an extension of a cored opening 34a in the body, which latter corresponds to the opening 34 in Fig. 3 formed by the core 32 in Fig. 2. If the opening 14a terminates within the plug, a simple turncock will be provided, but if it is extended all the way through the plug, as is also indicated in the drawing, the valve will open in two positions in the revolution of the plug. If passage 38 were joined to a passage 14a within the body of the plug and the latter were then turned and the plug and body again pierced by an opening extending entirely through the body to the left in the figure, a three-way cock would be provided.

In Fig. 5 I have shown a plug body 16b having a covering 40 applied thereabout prior to the molding operation. Such a covering 40 might, for example, be anti-friction material such as a graphic composition or a yieldable material such, for example, as a suitable compound of fiber and synthetic resin adapted to form a packing. The plug, as shown in Fig. 5, being suitably treated to prevent adherence of the moldable material thereto, is positioned in a mold as before and a body 8b molded thereabout, as shown in Fig. 6, which corresponds to Fig. 3 and the valve is completed, as already explained, by piercing the opening through the body and through the plug together with its investment 40. The resultant plug is completely packed immediately adjacent to the ports, around the stem 24a and throughout its body.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A method of making a turncock which includes a casing and a plug rotatable therein, which method comprises providing a plug, a portion at least of which is a solid of revolution hav-

ing a blank wall, molding a plug casing about said portion in nicely fitting but non-adherent relation and piercing through the casing and directly into and through the blank wall of the therewith assembled plug to provide a fluid passage controllable by relative rotation of the plug and casing.

2. A method of making a turncock which includes a casing and a plug rotatable therein, 10 which method comprises providing a plug, a portion at least of which is a solid of revolution having a blank wall, assembling one or more gaskets on said portion, molding a plug casing about said portion and the gaskets in nicely fitting but non-adherent relation to the former and piercing through the casing and directly into and through the blank wall of the therewith assembled plug at a location removed from the gaskets to provide a fluid passageway controllable by relative 20 rotation of the plug and casing.

3. A method of making a turncock which includes a casing and a plug rotatable therein, which method comprises providing a plug, a portion at least of which is a solid of revolution 25 having a blank wall, providing said portion with a nicely fitting investing covering layer of yieldable material of substantial thickness, molding a plug casing about said portion and covering layer in nicely fitting relation thereto, the layer 30 being in non-adherent relation to one of the parts and piercing through the casing and directly into and through the blank of the therewith assembled covered plug to provide a fluid passageway controllable by relative rotation of the plug and casing.

4. A method of making a turncock which includes a casing and a plug rotatable therein, which method comprises providing a plug, a portion at least of which is a solid of revolution having 40 a blank wall, covering at least a portion thereof with a covering layer of anti-friction material of substantial thickness, molding a plug casing about said portion and covering layer in nicely fitting relation thereto, the layer being in non-adherent relation to one of the parts and piercing through the casing and directly into and through the blank of the therewith assembled covered plug to provide a fluid passageway controllable by relative rotation of the plug and casing.

5. A method of making a rotary valve which comprises producing united and relatively rotatable inner and outer parts having opposed blank walls corresponding to a solid of revolution by 55 performing one of the elements and molding the other in direct contact with but in non-adherent relation to the first and by then piercing the parts through said walls in direct succession to provide a fluid passageway controllable by relative rotation of said parts.

6. A method of making a rotary valve comprising inner and outer relatively rotatable parts characterized by molding one directly upon the 65 other in nicely fitting and inseparable but non-adherent and rotatable relation thereto and thereafter piercing the so assembled parts to provide a fluid passageway controllable by relative rotation of said parts.

JOSEPH C. FULLER.
